Edward Pilkim
Sellers Patent

The whole referred to in this Sellers Patent and, making part of the same and giving a description in the words of the said Edward Pilkim himself of his improvement in the mode of repairing fences.

This improvement consists in backing or applying the Post, when the bottom are rotted off. A quarter of a round but of any tree that is suitable for posts and about seven feet long is sawed in a slanting direction half across about $2\frac{1}{2}$ feet from one end and on the opposite side the same distance from the other end, and then split apart from one sawing to the other or making two back pieces with a but to stand in the ground.

In case such timber is used as will not split, it may be sawed or hewed into a square shape of about 2 ft. in each diameter and sawed diagonally from about 2 ft. of one end to about 2 ft. of the other end.

To repair a post when rotted off at the bottom, the post is raised up and kept in its place at the height wanted. The backing piece set in the ground so as that the shoulder will be a little out of the ground, and then fastened to the back of the post by two or more spikes (cut men preferred). Then a five hole post is rotted off so as to destroy the bottom hole. The centre of the post may be cut out up to the next hole, and a backing piece cut off and slanted so as to fit in the end, coming up so as to form a button hole and a spike driven thru the sound part of the post on each side, making in this way a four holed post.

Posts to fences of all descriptions may be repaired in this way.

East Hartford Nov 12th 1828.
